R. U. Richards,

Making Shoe Pegs.

Patented May 23, 1812.

Robert H. Richards
Letters Patent

1741X

117

The Schedule referred to in these Letters Patent and making
part of the same containing a description in the words of the said Robert H. Richards
himself of his improvement in making Woods & Trees by using wooden pegs made with screws
or notches or creases

The said work being made with wooden screws, which screws being driven in the
holes and slots after an angle. The said screws being made in a machine which is made part
of this invention this machine consists in a number of important principles. I have a frame
with four posts at the corners being framed at the bottom to a plank. This machine is one
foot and six inches long and high and eight inches wide the sides consist of two sticks of
timber being framed in the posts. The running work consists of two wheels one foot diam-
eter and two whines being geared so as to add to the velocity, sixteen to one of the wheels all
run on iron shafts one shaft has two cranks one to put the machine in motion and the
other crank to work the cutter, the shaft to run on forged heads so that by screws as to
tighten or loosen the bushes or belts. I have a spindle where I work my screws. The spindle
is eight inches long and hollow so as to have the stick run in the centre; on the end of the
spindle I have two, bronze whored by on my boy to set the screw; the boy is made similar
to a ring box to cut a wooden screw. I have a part of the boy where I set the screw of brass
or iron so as not to wear, with a thread - - - - - cut in the boy to receive the screw
my cutter to cut off the sound has its motion from the first wheel by a small crank;
from that motion I have a chisel or knife that goes against a solid post, the post stands
perpendicular with a hole in it to receive the screw rods, then the chisel works at the
bottom of the post and cuts them a suitable length for driving by means of a gauge board
or ironed by a screw. I find this machine can be varied a number of ways, I may go
with one large wheel single geared or small wheels double geared the boy to turn a span-
ner but I prefer the spindle and boy to turn and the machine to be made and to have
these can be octagonal or square pegs can be creased or dented but I can in all cases
at pegs or turned round or square this machine can be made to turn out a number of
screws at a time
